UNITED STATES PATENT OFFICE.

DAVID BROWN WHITEHILL, OF NORTH CLARENDON, PENNSYLVANIA.

WELL-BAILING-OPERATING MECHANISM.

No. 850,987.

Specification of Letters Patent.

Patented April 23, 1907.

Application filed May 24, 1906. Serial No. 318,500.

To all whom it may concern:

Be it known that I, DAVID BROWN WHITEHILL, a citizen of the United States, residing at North Clarendon, in the county of Warren and State of Pennsylvania, have invented a new and useful Well-Bailing-Operating Mechanism, of which the following is a specification.

This invention relates more particularly to mechanism for raising and lowering the bails in oil-wells, but can unquestionably be employed in other relations where hoisting or cable-winding mechanism is useful.

One of the principal objects is to provide a comparatively simple and novel structure that is entirely effective for elevating and lowering the bails, or, in fact, any other articles or devices, said structure being particularly adapted to operate such bails and be controlled at a distance, thereby permitting the machine to be used in bailing out wells that are scattered over a comparatively large area.

The preferred form of construction is illustrated in the accompanying drawings, wherein—

Figure 1 is a view in elevation of the structure. Fig. 2 is a top plan view of the same. Fig. 3 is a longitudinal sectional view therethrough. Fig. 4 is an end elevation with the driving means removed. Fig. 5 is a sectional view on the line 5 5 of Fig. 1. Fig. 6 is a detail sectional view through one end of the actuating-stem. Fig. 7 is a detail view on the line 7 7 of Fig. 4.

Similar reference-numerals designate corresponding parts in all the figures of the drawings.

In the embodiment illustrated a suitable frame is employed, which in the present structure comprises a base 8, having standards 9. At one end of the frame is located a driving-shaft 10, which is continuously operated from any suitable source of power and has secured thereto a driving-wheel 11. The hub 12 of this driving-wheel projects beyond the shaft 10, forming a socket 13. A hollow drum-shaft 14 is journaled in the frame and is disposed in line with the driving-shaft 10. The bearings for the shaft 14 consist of spaced boxings 15, that surround said shaft and contain rollers 16. The boxings 15 are vertically adjustable on the standards 9 and are arranged to be held in adjusted relation by bolts 17, passing through slots 18 in said standards. Adjusting-screws 19, journaled

in offset ears 20 on the upper ends of the standards, have threaded engagements with ears 21, carried by the boxings, said screws thus serving to raise or lower the bearings. 60

The shaft 14 carries between the bearings a pair of drum-heads 22, having hubs 23, that are fixed to the shaft by set-screws 24 or by any other suitable means. The outer ends of these hubs are beveled, as shown at 25, and 65 said outer ends engage the inner portions of the inner ends of the rollers, as will be evident by reference to Fig. 3. A thrust-bearing member 26 is secured to one end of the shaft and has a hub 27, provided with a beveled 70 inner end 28, that engages the inner portions of the outer ends of the adjacent rollers, as shown in Fig. 3. A brake-wheel 29 is secured to the opposite end of the shaft and has a hub 30, provided with a beveled end 75 31, that engages the outer ends of the rollers of the other bearing. The above-described structure and relation of parts are important.

It has been found that with the roller-bearings as ordinarily constructed the rollers 80 have a tendency to take positions in angular relation to the shaft instead of parallel thereto. By having the beveled ends of the various hubs, however, engaging the inner portions of the roller end this tendency is overcome, and experience has demonstrated that the rollers will remain parallel to the shaft. 85 In this connection it is to be noted that parts of the hoisting mechanism constitute the means for thus retaining the rollers. 90

Clutch mechanism is mounted on the outer face of the brake-wheel 29. In the present embodiment carrier-blocks 32 are adjustably mounted on said outer face and are movable toward and from the axis of rotation of the 95 wheel. These blocks are held in adjusted position by bolts 33, passing through slots 34 therein and into the wheel. Guide-lugs 35, carried by the inner sides of the blocks, engage in slots 36 in the wheel, and an adjusting-screw 37, threaded in the outer end of each block and bearing against one of the bolts 33, constitutes the means for adjusting each block. Pivoted on the carrier-blocks 32 are jaws 38, the outer faces 39 of which are curved, as shown, said jaws being movable into and out of engagement with the inner face of the driving-wheel 11. The outer ends of the jaws are provided with guide-plates 40, having slots 41, through which pass 105 guide-studs 42. Springs 43, secured to the outer ends of the plates 40 and to the wheel, 110

serve to urge the jaws inwardly away from the driving-wheel 11.

Thrust-bars 44 are slidably mounted in keepers 45, secured to the brake-wheel 29. 5 The outer ends of the thrust-bars engage the inner sides of the jaws, their inner ends having heads 46, that are movable toward and away from each other. An actuating-stem 47 is longitudinally slidable in the hollow drum-shaft 14. One end of this shaft carries a tapered head 48, that is movable between the heads 46 of the thrust-bars, so as to separate said bars, and thereby swing the jaws 38 outwardly against the tension of the 15 spring 43. A guide-pin 49 is preferably mounted in the head 48 and is removable therefrom, said pin extending between the heads 46 and having a retaining-head 50. This pin, together with the head 48, operates 20 back and forth in the socket 13, formed in the hub of the driving-wheel. The opposite end of the stem 47 is provided with an annular groove 51, in which is engaged a yoke 52. This yoke is pivotally mounted on a lever 53, fulcrumed at its lower end upon the base 8 and having its upper end disposed adjacent to a post 54. It will be evident that when the lever 53 is swung in one direction the stem 47 will be moved longitudinally within 25 the drum, the head 48 will spread the thrust-bars 44 apart, and the jaws will engage the driving-wheel, thus clutching the drum to the driving means. In order to prevent the longitudinal movement of the drum with the 30 stem, it will be observed that the heads 46 of the thrust-bars 44 are abutted against the hub 12 of the driving-wheel 11, as shown in Fig. 3, and, furthermore, this end thrust or movement is prevented by a bracket or 35 keeper 55, secured to one of the standards 9 and embracing a flange 56 on the thrust member 26. It is also to be observed that by adjusting the carrier-blocks 32 toward and from each other the outer ends of the 40 thrust-bars 44 may be made to engage the jaws 38 at different distances from their ends, thereby varying the force exerted on said 45 jaws.

Brake mechanism is also associated with 50 the drum. In the present embodiment this brake mechanism consists of a band 57, that surrounds the brake-wheel 29 and is held in place by suitable guides 58. One end of the band is secured against movement to the 55 frame, as shown at 59. The other end is connected, as shown at 60, to a reciprocating shank 61, mounted on the frame and movable in a vertical direction. An actuating-lever 62, fulcrumed on the frame, has a link 60 connection 63 with the shank 61. This lever 62 extends transversely of the lever 53 and has its free end disposed adjacent to the post 54. A cable 64, connected to the free end of the lever 62, also has a connection, as 65 shown at 63^a, with the upper end of the post

54, and a pulley 65, carried by the upper end of the lever 53, operates on the cable 64. An actuating-cable 66, passing around a guide-sheave 67, also passes around a pulley 68 on the lever 53. One end, as 69, of the cable 70 66, is secured to the supporting-frame. The other end of said cable is located at the well which is being bailed, and consequently the said cable 66 can be extended in any direction desired. The bail-operating cable is 75 shown at 70 and is of course wound upon the drum formed by the shaft 14 and the two heads 22.

The operation of the structure may be briefly described as follows: The driving 80 shaft and wheel are continuously rotated by any suitable means, as already described. As long as the head 48 of the actuating-stem 47 is withdrawn from the thrust-rods 44 the jaws 38 are out of contact with the driving-wheel, and consequently the hoisting mechanism is not operated. If the cable 66 is loose, the lever 62, which is provided with a suitable weight, as 62^a, is in its lowermost position. Consequently the band 57 will bind 85 upon the wheel 29 and hold the drum against rotation. If it is now desired to wind the cable upon the drum, the operator has only to draw upon the cable 66, whereupon the lever 53 will be moved to carry the head of the stem 47 between the thrust-rods, thus 90 swinging the jaws into engagement with the driving-wheel. A swinging movement of the lever 53 carries the pulley 65 away from the post 54, and as a result the lever 62 will be elevated, thereby loosening the brake-band. When it is desired to stop the drum and hold 95 it, it is only necessary to release the cable 66, whereupon, as already described, the jaws will be disengaged from the driving-wheel 100 and the brake-band applied to the driving-wheel. On the other hand, if it is desired to lower the bail into the well then the cable 66 is held so that the lever 53 is in an intermediate position, in which case the jaws 38 will 105 be out of engagement with the driving-wheel and the brake-band 57 will be sufficiently loose to permit the drum to turn freely.

From the foregoing it is thought that the construction, operation, and many advantages of the herein-described invention will 110 be apparent to those skilled in the art without further description, and it will be understood that various changes in the size, shape, proportion, and minor details of construction may be resorted to without departing from the spirit or sacrificing any of the advantages of the invention.

Having thus fully described my invention, what I claim as new, and desire to secure by 115 Letters Patent, is—

1. In mechanism of the class described, the combination with a winding-drum, of driving means, a clutch for connecting the drum and the driving means, a lever for ac- 120

tuating the clutch, a brake for the drum, a lever for actuating the brake, connections between the levers for effecting the movement of one on the movement of the other, 5 said connection being movably engaged with one lever, and actuating means movably engaged with the other lever.

2. In mechanism of the class described, the combination with a winding-drum, of 10 driving means therefor, clutch mechanism for connecting the drum to the driving means, a lever for actuating the clutch mechanism, a brake for the drum, and a lever for actuating the brake, one of said levers having 15 a cable connected thereto, the other having a slidable engagement with the cable.

3. In mechanism of the class described, the combination with a winding-drum, of 20 driving means therefor, clutch mechanism for connecting the drum to the driving means, a lever for actuating the clutch mechanism, a brake for the drum, a lever for actuating the brake, a cable connected at one end to the free end of one lever and having a fixed 25 connection at the other end, the other lever having a slidable engagement with said cable, and another cable connected to said other lever for actuating the same.

4. In mechanism of the class described, 30 the combination with a driving-shaft having a driving-wheel, of a drum having a brake-wheel disposed adjacent to the driving-wheel, clutch mechanism carried by the brake-wheel and coacting with the driving-wheel, a stem operating in the drum for moving the clutch mechanism, a lever connected to the stem, a brake-band operating on the brake-wheel, a reciprocatory shank connected to the band, a lever connected to 40 the shank, a cable connected to said lever, the stem-actuating lever having a movable engagement with said cable, and a cable connected to the stem-actuating lever for operating the same.

45 5. In mechanism of the class described, the combination with a hollow winding-drum, of a brake-wheel carried thereby, a brake-band coacting with the brake-wheel, a lever for operating the brake-band, clutch mechanism mounted on the brake-wheel, an 50 actuating-stem for the clutch mechanism operating in the winding-drum, and means for simultaneously operating the brake-lever and stem.

55 6. In mechanism of the class described, the combination with a hollow winding-drum, of a brake-wheel carried thereby, a brake-band coacting with the wheel, a lever for operating the brake-band, clutch mechanism mounted on the wheel, an actuating-stem operating in the winding-drum for moving the clutch mechanism, a lever engaging the stem, and means associated with the stem-actuating lever and the brake-band 60 lever and operating upon movement in one

direction to effect the release of the brake-band and to apply the clutch mechanism, and upon the reverse movement to release the clutch mechanism and apply the brake-band.

7. In mechanism of the class described, the combination with a driving-shaft having a driving-wheel, of a drum comprising a hollow shaft independent of the driving-shaft and having a brake-wheel located adjacent to 70 the driving-wheel, clutch mechanism mounted on the brake-wheel and coacting with the driving-wheel, an actuating-stem for the clutch mechanism mounted in the drum-shaft and longitudinally movable therein, 75 and a brake-band coacting with the periphery of the brake-wheel.

8. In mechanism of the class described, the combination with a driving-shaft, of a driving-wheel mounted thereon and having a hub projecting beyond the shaft, forming a 80 socket, a drum including a hollow shaft journaled in line with the driving-shaft, a wheel carried by the hollow shaft and located adjacent to the driving-wheel, jaws pivoted upon 85 the drum-wheel and swinging into and out of coaction with the driving-wheel, thrust-bars bearing against the hub of the driving-wheel and operating against the jaws for moving the same, an actuating-stem longitudinally 90 movable in the driving-shaft and having a tapered end that moves between the thrust-bars, and means for longitudinally moving the stem.

9. In mechanism of the class described, 95 the combination with a drum comprising a shaft, of a journal-boxing for the shaft, rollers located in the boxing, a drum-head member fixed to the shaft on one side of the boxing and having a hub provided with a beveled 100 end that engages the inner portion of the adjacent ends of the rollers, and another member fixed to the shaft on the opposite side of the boxing and having a hub provided with a beveled end that engages the inner portions 105 of the opposite ends of the rollers, driving means, and clutch mechanism for connecting the driving means to the drum.

10. In mechanism of the class described, 110 the combination with a drum including a shaft, spaced boxings surrounding the shaft, rollers located in the boxings, drum-heads secured to the shaft between the boxings and having hubs provided with beveled ends that engage the inner portions of the inner ends of 115 the rollers, a brake-wheel secured to the shaft on the outer side of one of the boxings and having a hub provided with a beveled inner end engaging the outer ends of the rollers, of clutch and brake mechanisms coacting with 120 the brake-wheel, and an end thrust member secured to the shaft on the outer side of the other boxing, said end thrust member having a hub provided with a beveled end that engages the outer ends of the adjacent rollers.

11. In mechanism of the class described, the combination with a driving-shaft, and a driving-wheel carried thereby, of a hollow drum-shaft, roller-bearings for the drum-shaft, a brake-wheel mounted on the drum-shaft at one side of the bearings, clutch mechanism mounted on the brake-wheel and co-acting with the driving-wheel an actuating-stem extending through the hollow drum-shaft and operating on the clutch mechanism, a lever connected to the stem, a brake-band surrounding the brake-wheel and co-operating therewith, means for operating the brake-band including a lever, cable connec-

tions between the levers for simultaneously operating them, an actuating-cable connected to one of the levers, drum-heads secured to the hollow shaft between the bearings, and a thrust-bearing member connected to the opposite end of the shaft to that carrying the brake-wheel.

In testimony that I claim the foregoing as my own I have hereto affixed my signature in the presence of two witnesses.

DAVID BROWN WHITEHILL.
